UNITED STATES PATENT OFFICE.

VICTOR M. ALLEN, OF WAVERLY, NEW YORK.

VENTILATING WINDOW-SHADE.

1,329,352.

Specification of Letters Patent.

Patented Feb. 3, 1920.

Application filed April 5, 1919. Serial No. 287,857.

To all whom it may concern:

Be it known that I, VICTOR M. ALLEN, a citizen of the United States, and a resident of Waverly, in the county of Tioga and State of New York, have invented certain new and useful Improvements in Ventilating Window-Shades, of which the following is a specification.

This invention relates to ventilating window shades and has for its object to provide a shade of this kind which is simple in construction, may be easily applied to a window frame, may be readily adjusted to admit or exclude light or sunshine, and which will automatically adjust itself in a wind so as not to be torn or displaced.

Another object is to provide a series of horizontal panels which may be operated in unison and simultaneously adjusted to any desired angle so as to admit light and air and exclude sunshine and the view of those within from the outside. The panels may, however, be quickly adjusted to permit those inside to look out when desired and to admit sunshine.

A further object is to provide means for protecting the shade from dust and the sun when not in use, said protecting means being capable of housing the shaft in compact form and permitting it to be quickly withdrawn for use when occasion requires.

Other objects will appear as the description proceeds.

The invention will be first hereinafter described in connection with the accompanying drawings, which constitute part of this specification, and then more specifically defined in the claims at the end of the description.

40 In the accompanying drawings, wherein similar reference characters are used to designate corresponding parts throughout the several views—

Figure 1 is an elevation of the frame and casing for the shade with the shade itself almost completely housed in the casing, the lower edge of said shade being left slightly protruding from the casing to be grasped for lowering the same.

45 Fig. 2 is a vertical section through the shaft applied to a window frame and showing the panels adjusted in one position for admitting light and air but excluding sunshine and screening those inside from view by those outside.

50 Fig. 3 is a detailed section of the window

frame and shade supporting frame, showing the weighted disk to which the panels are connected for adjusting them to different angles and which is adapted to yield in the wind to prevent the shade from being torn or displaced.

Fig. 4 is a detailed view of said weighted disk looking at the other face thereof.

Fig. 5 is a sectional view of the weighted disk in association with its supporting bracket and the pin on the panel bow which is designed to engage any one of a series of sockets in the face of the wheel.

Fig. 6 is an end view of the casing for housing the shade when rolled up, showing more particularly the door or closure for said casing; and

Fig. 7 is a longitudinal section through one end of said casing and closure.

The curtain comprises a plurality of horizontal panels 1, made of textile or other suitable material, and having their inner edges connected at intervals to vertical side strips 2 of similar material, one of said strips being designed to extend along each side of a window frame 3, as indicated in Fig. 2 when the shade is in use. The inner and outer edges of each panel are reinforced and held in position by horizontal spring wires or rods 4, preferably run through the hems at said edges of said panels. The upper panel is extended upwardly, as at 5, and attached to a shaft 6, arranged in a horizontal tubular housing or casing 7 attached to the upper edge portion of a metal frame 8 over which the shade works and which may be readily fastened to a window frame by screws 9, Fig. 2, engaging slots 10 and 11 in said metal frame, Fig. 1.

The lower portion of the casing 7 is open to permit the shade to be wound up in the same or withdrawn therefrom as occasion requires. This open portion of the casing is normally closed, however, by a door or closure 12 which has end flanges 13 bent over the ends of the casing, as shown in Figs. 6 and 7, permitting said door or closure to be swung upon the casing as its axis for closing or uncovering the open lower portion of said casing. The door or closure 12 depends for some distance below the casing 7, and normally its lower edge bears against the shade, as shown in Fig. 2, for holding it close up to the window. The shaft 6 may have a crank 14 protruding from one end of the casing for rolling up the shade.

The outer edges of the panels 1 are connected together by cords 15 attached to the corners thereof at intervals corresponding to the intervals between the inner edges of 5 said panels on the strips 2. The outer edge of the top panel is connected to arms 16 depending from a rock shaft 17 extending across the frame 8. The free ends of said arms are bent inward at 18, Fig. 1, to detach- 10 ably engage the outer edge of said upper panel, so that the arms may be detached from the shade when the latter is to be rolled up. By swinging the arms 16 on the rock shaft the upper panel may be adjusted to 15 any desired angle, and owing to the cord connections 15 between the several panels, all of said panels will be adjusted in unison so as to be arranged substantially parallel to one another.

20 To retain the panels in adjusted position, the arm 16 at one side of the shade is provided with a pin 19 adapted to engage any one of an arcuate series of sockets 20 in the face of a disk or wheel 21 which is also carried by the rock shaft 17. Said disk or wheel 21 is weighted at 22 at the bottom in order to normally maintain the panels of the shade at a set position, but if said panels are caught by the wind the disk will yield or 25 rotate to prevent the shade from being torn or displaced. The rock shaft may be journaled in a bracket 23 at one side of the frame 8 and in a lug 24 at the other side thereof, or mounted in any other suitable 30 way.

The wire or rod which is run through the hem at the inner edge of the lowest panel has its ends extended beyond the ends of said panel and bent to form a bow with arms 25 40 corresponding in length to the arms 16. The free ends of the arms 25 have spaced angularly extending pins or studs 26 and 27. The studs 26 at the extreme ends of the arms are designed to be engaged with eye lugs 45 28 on the lower portion of the frame 8, Figs. 1 and 2, when the shade is in use, and the studs 27, are intended to be hooked over the lateral edges of the lowest panel, as shown in Fig. 2, for holding the bottom portion 50 of the shade close to the frame 8. When the shade is to be rolled up in the casing 7, the studs 26 are disconnected from the eye lugs 28 on the frame, and after the shade has been rolled up, as shown in Fig. 1, the 55 arms 25 will depend from the lower edge of the same and be supported thereby near the frame 8.

When used on an open window, the shade may be readily adjusted with its panels at 60 an upwardly or downwardly inclined angle so as to admit light and air but exclude sunshine and prevent view of persons inside by those outside. The panels may also be adjusted to admit sunshine and to permit the 65 occupants of the room to see out, if desired.

Inasmuch as the wind has free passage through the shade between the panels, said shade will not be blown about or displaced like an ordinary shade. When the shade is used on a closed window, its operation is 70 the same, the only difference being that air is not admitted with the light. Of course, the panels may be dropped to vertical overlapping position whenever it is desired to darken the room. It will be observed that 75 the shade is mounted complete on the frame 8 and may be quickly attached to any window frame by simply inserting the necessary screws 9 in the latter to engage the slots 10 and 11.

Having thus fully described my invention, what I claim as new and desire to secure by Letters Patent of the United States, is—

1. The combination with a frame to be attached to a window frame and surround 85 a window opening, of a ventilating window shade mounted on said first mentioned frame and comprising a plurality of spaced panels of flexible material and strips to which the inner edges of said panels are attached at 90 intervals, means connecting the outer edges of the panels together in spaced relation similar to the spacing of their inner edges along the strips, and means for adjusting the upper panel at various angles, thereby 95 simultaneously adjusting the lower panels to correspond.

2. The combination with a frame to be attached to a window frame and surround a window opening, of a ventilating window 100 shade mounted on said first mentioned frame and comprising a plurality of spaced panels of flexible material, means for moving said panels in unison to set them at various angles, and means for retaining the panels 105 in set position.

3. The combination with a frame to be attached to a window frame and surround a window opening, of a ventilating window shade mounted on said first mentioned 110 frame and comprising a plurality of spaced panels of flexible material, means for moving said panels in unison to set them at various angles, and means for normally retaining the panels in set position but adapted to 115 yield under the influence of the wind for the purpose specified.

4. The combination with a frame to be attached to a window frame and surround a window opening, of a ventilating window 120 shade mounted on said first mentioned frame and comprising a plurality of spaced panels of flexible material, means for moving said panels in unison to set them at various angles, and means for normally retaining the panels in set position, but adapted to yield under the influence of the 125 wind and automatically return them to normal position after the wind subsides.

5. A ventilating window shade compris- 130

- ing a plurality of spaced panels of flexible material, in combination with pivoted arms for supporting the outer edge of the top panel, pivoted arms engaging the outer edge 5 of the bottom panel, and means connecting the outer edges of the panels together so that they will move in unison. 40
6. A ventilating window shade comprising a plurality of spaced panels of flexible material, in combination with pivoted arms 10 detachably connected to the outer edge of the top panel, a frame on which said arms are mounted, arms connected to the outer edge of the bottom panel and detachably 15 pivoted to said frame, and means connecting the outer edges of the panels together so that they will move in unison. 45
7. A ventilating window shade comprising a plurality of spaced panels of flexible material, in combination with pivoted arms 20 detachably connected to the outer edge of the top panel, a frame on which said arms are mounted, arms connected to the outer edge of the bottom panel and detachably 25 pivoted to said frame, studs on said latter arms to hook over the inner edge portion of the bottom panel for holding it close to the frame, and means connecting the outer edges 30 of the panels together so that they will move in unison. 50
8. The combination with a window shade having a panel, of pivoted arms connected to the outer edge of said panel for supporting the same, a casing having an opening 35 through which the shade may be drawn, and a closure for said opening swiveled on the casing and normally engaging the shade adjacent the pivoted ends of the arms for 45
- holding the inner edge of the panel in position. 55
9. The combination with a window shade having a panel, of pivoted arms connected to the outer edge of said panel for supporting the same, and means for fastening said arms at different angles. 60
10. The combination with a window shade having a panel, of pivoted arms connected to the outer edge of said panel for supporting the same, and means for fastening said arms at different angles, said fastening 50 means being capable of yielding to the action of the wind and automatically returning the panel to normal position after the wind has subsided. 65
11. The combination with a window shade having a panel, of pivoted arms connected to the outer edge of said panel for supporting the same, a rotatable disk mounted concentric with the pivots of said arms and having an arcuate series of sockets therein, 60 a weight on the disk, and a pin on one of said arms to engage said sockets, the disk being adapted to yield and rotate under the action of the wind on the panel, and the weight adapted to automatically return the 65 disk and panel to normal position after the wind subsides. 70
12. The combination with a frame to be attached to a window frame and surround a window opening, of a shade mounted on said frame, means for connecting the shade to the frame at the top and bottom, and a casing also carried by the frame and adapted to house the shade when not in use. 75
